UNITED STATES PATENT OFFICE.

FRANK HAYES, OF PASADENA, CALIFORNIA.

SELF-CENTERING HYDRAULIC BEARING.

1,238,515.

Specification of Letters Patent. Patented Aug. 28, 1917.

Application filed June 12, 1916. Serial No. 103,192.

To all whom it may concern:

Be it known that I, FRANK HAYES, a citizen of the United States, residing at Pasadena, in the county of Los Angeles and 5 State of California, have invented a new and useful Self-Centering Hydraulic Bearing, of which the following is a specification.

This invention relates to improvements in self-centering hydraulic bearings for rotary 10 pumps and resides in the provision of a simply constructed bearing which will automatically center the pump and prevent vibration, thus eliminating the use of mechanical bearings and their inherent 15 troubles due to friction, wear and vibration.

Another object is to generally improve hydraulic bearings for pumps so as to render them more reliable, efficient and positively self-centering by providing a pocket 20 in the bearing which will retain a portion of the liquid being pumped, thus making the bearing positive in action from the start without waiting for the liquid being pumped to reach the upper bearings above 25 the level from which liquid is being pumped.

Other objects and advantages may appear from the subjoined detail description.

The accompanying drawings illustrate the invention.

30 Figure 1 is an enlarged fragmentary sectional view;

Fig. 2 is a horizontal sectional view on line 2—2 of Fig. 1; and

Fig. 3 is a horizontal sectional view taken 35 on line 3—3 of Fig. 1.

Referring to the drawings, 1 designates a pump tubing or casing comprising sections 2 and 3 which are joined by a coupling sleeve 4. The sleeve 4 comprises sections 5 40 and 6 respectively. The section 5 is considerably longer than the section 6 and is provided with internal screw-threads 7 at its upper end to receive the screw-threaded lower end of the section 2 of the casing, 45 said screw-threads being formed so as to define a shoulder 8 which abuts the lower end of the section 2. The lower end of the section 5 of the sleeve is internally screw threaded and receives the reduced screw 50 threaded portion 9 of the lower section 6. The reducing of the section 6 provides a shoulder 10 upon which the lower end of the section 5 rests, said sections 5 and 6 being flush upon their outer surfaces. The 55 lower end of the section 6 is internally screw-threaded as at 11 as is the upper end

of the section 5 and receives the upper end of the section 3 of the casing.

The lower section 6 of the sleeve 4 extends upwardly into the upper section 5 and is 60 offset or reduced as at 12 and spaced from the section 5 so as to provide an annular pocket 13 which is closed at its lower end and open at its upper end.

The upper section 5 is provided with 65 radial deflecting vanes 14 which are integral with a collar 15 located centrally of the sleeve 4 and with said sleeve. A rotary pump shaft 16 extends through the collar 15 and into the hub member 17 of a propeller 18. The hub member 17 is provided with a reduced extension 19 which is internally screw-threaded and extends upwardly into the collar 15 but is spaced circumferentially from said collar, there being provided an opening 20 to receive said extension. The shaft 16 is turned in the screw-threaded portion 19. A transverse groove 22 is formed in the upper end of another section 23 of the shaft 16, and said 70 section 23 is extended through a spider 24 carried by the lower section 6 and upwardly into the hub 17. The upper end of the section 23 is screw threaded as at 25 and cooperates with the internal screw-threaded 75 hub 17 so that when the shaft 16 including the section 23 is rotated the propeller 18 and hub 17 thereof will be rotated.

The blades 26 of the propeller are joined at their outer ends with a cylindrical bearing shell 27 which is of slightly less diameter than the inside diameter of the sleeve and is spaced circumferentially from said sleeve. The lower portion of the shell 27 is located within the pocket 13 in equidistantly spaced relation to the walls of the pocket so that the shell may rotate without coming into contact with said walls. In this connection it will be noted that the blades 26 of the propeller, hub 17 and the 90 shell 27 are free from contact with the sleeve 4, spider 24, deflecting vanes 14 and collar 15. The shafts 16 and 23 are loosely mounted in the bearings therefor. This arrangement and construction is provided to 95 eliminate friction, vibration and undue wear on the parts of the devices as will be later 100 more fully described.

In practice, any number of propellers and bearings therefor, such as hereinbefore described, may be used. The liquid lifted up 110 or pumped by the propeller 18 is permitted

access to the pocket 13 and space between the upper portion of the shell 27 and opposed portion of the sleeve 4, since the shell 27 is completely spaced from the casing and sleeve 4. When the propeller is rotated the liquid in the pocket 13 is equally distributed upon both sides of the portion of the shell 27 that is located within the pocket and the centrifugal action of the liquid serves to hold the propeller 18 and shell 27 centered. Should the shell 27 move off the center the resistance offered it owing to the displacement of the liquid will cause an immediate centering of the shell and coöperating parts. 15 The liquid in the pocket 13 and between the shell and sleeve 4 provides what might be termed a wedging action when the device is not centering properly.

The vanes 14 act to curb the rotative tendency of the liquid which is lifted upwardly by the propeller 18 and cause the liquid to be forced upwardly without swirling to any extent. When the propeller 18 is rotated the liquid is lifted upwardly and also given 25 a rotary motion. The diffusion vanes 14 catch the liquid as it leaves the propeller and convert the rotary motion into a vertical motion, thus increasing the efficiency of the pump and eliminating the friction 30 caused by the swirling of the liquid. The arms of the spider 24 act as guide vanes and keep the liquid from whirling as it enters the propeller, thus making the pumping action more effective on the liquid. This 35 eliminates wear and friction between the water and casing, permits the liquid to pass up the casing freely and without undue obstruction.

The liquid finds its way to the spaces between the rotating and stationary parts of the pump and as said spaces are of equal dimensions relative to the respective parts a balancing or centering of the rotating parts is had. Friction is thus reduced to 40 the minimum since the liquid acting as a bearing is rotated with and by said rotating parts.

It will be seen with reference to the foregoing description and accompanying drawings that I have provided a rotary hydraulic pump in which the rotating parts do not come into bearing contact with the stationary parts and all undue wear and lost motion is therefore eliminated. Aside from 45 this feature the device may be readily assembled and disassembled so that parts may be renewed when necessary.

My invention also overcomes the difficulty of oiling the bearings which are below the 50 top of the well since lubrication in my device is not required.

I claim:

1. A self-centering hydraulic bearing for rotary pumps comprising casing sections, a coupling in two sections removably con-

nected with one another, connecting the casing sections, the lowermost of the coupling sections extending into the upper section and being offset and spaced circumferentially from said upper section to provide an 70 annular pocket opening at its upper end and closed at its lower end, a rotary shaft mounted within the casing and extending through the coupling, a pump carried by the shaft, and a peripheral shell on the 75 pump extending into the pocket and being spaced from the coupling and walls of the pocket formed therein.

2. In a self-centering hydraulic bearing for vertical rotary pumps, a well casing in 80 sections, a coupling in two sections connecting the casing sections, one of said coupling sections extending into and being spaced circumferentially from the other coupling section to provide an annular pocket opening at its upper end, a shaft mounted within the casing and coupling, a propeller carried by the shaft, and a peripheral shell carried by the propeller and extending into the 85 pocket and being spaced from the walls thereof.

3. In a self-centering hydraulic bearing for vertical rotary pumps, a well casing in sections, a coupling in two sections connecting the casing sections, one of said coupling sections extending into and being spaced circumferentially from the other upper end, a shaft mounted within the casing and coupling, a propeller carried by the shaft, a peripheral shell carried by the propeller 95 and extending into the pocket and being spaced from the walls thereof, said shaft being in sections having screw-threads meeting interlocked ends, and a screw-threaded hub for said propeller being 100 turned upon the screw-threads of the ends of the shaft sections to hold the sections in interlocked position.

4. In a self-centering hydraulic bearing for vertical rotary pumps, a well casing in 110 sections, a coupling in two sections connecting the casing sections, one of said coupling sections extending into and being spaced circumferentially from the other upper end, a shaft mounted within the casing and coupling, a propeller carried by the shaft, a peripheral shell carried by the propeller and extending into the pocket and being spaced from the walls thereof, said shaft being in sections having screw-threads meeting interlocked ends, and a screw-threaded hub for said propeller being turned upon the screw-threads of the ends of the shaft sections to hold the sections in interlocked position, 115 said coupling sections being connected by screw-threads.

5. In a self-centering bearing for vertical rotary pumps, a well casing in sections, a coupling comprising two sections connecting the ends of the well casing, one 130

of said coupling sections being removably connected with and extending into the other section and spaced circumferentially therefrom to provide an annular pocket opening at its upper end, a bearing supported by the last named section, a shaft loosely mounted in the bearing, a bearing carried by the second named coupling section and loosely receiving the shaft, deflecting vanes connected with the second named coupling section and supporting the last named bearing, a pro-

peller located between the bearings and carried by the shaft, and a peripheral shell carried by the propeller and extending into and being spaced from the walls of the 15 pocket and the walls of the coupling.

Signed at Los Angeles, California, this 6th day of June, 1916.

FRANK HAYES.
